UNITED STATES PATENT OFFICE

MORRIS BORDMAN, OF PHILADELPHIA, PENNSYLVANIA

DESIGN FOR A PACKAGED ANTIMOTH CAKE AND DEODORANT

Application filed May 26, 1932. Serial No. 43,907. Term of patent 14 years.

To all whom it may concern:

Be it known that I, MORRIS BORDMAN, a citizen of the United States, and a resident of Philadelphia, in the county of Philadelphia and State of Pennsylvania, have invented a new, original, and ornamental Design for a Packaged Anti-Moth Cake and Deodorant, of which the following is a specification, reference being had to the accompanying drawing, forming part hereof, in which:

Figure 1 is a plan view of a packaged anti-moth cake and deodorant shown in the completely assembled condition.

Figure 2 is a top perspective view of Figure 1.

In the drawing, 1 designates a box or package having the ornamental cover 2 bearing the floral representation 3 simulating the

stem and leaves of a flower and having a cut out portion 5 therein which represents the shape of the petals of the flower. 7 represents the article to be packaged in the box 1, the upper surface of said article simulating in relief the appearance of the flower, the contour of which is defined by the cut out portion 5. The ornamental configuration 3, the cut out portion 5, and the coacting portion of the article to be packaged, all combine to produce a composite, aesthetic appearance embodied in a unitary article.

I claim:

The ornamental design for a packaged anti-moth cake and deodorant, as shown and described.

In testimony whereof, I affix my signature.

MORRIS BORDMAN.
